UNITED STATES PATENT OFFICE

97,907

DESIGN FOR A DISPLAY DEVICE

Lionel A. Carter, St. Louis, Mo., assignor to
Paddy Novelty Company, St. Louis, Mo.

Application March 16, 1935, Serial No. 55,897

Term of patent 3½ years

To all whom it may concern:

Be it known that I, Lionel A. Carter, a subject of Great Britain and a resident of the city of St. Louis and State of Missouri, have invented a new, original, and ornamental Design for a Display Device, of which the following is a specification.

In the accompanying drawing,

Fig. 1 is an elevation of a display device showing my design,

Fig. 2 is a similar view looking in the opposite direction; and

Fig. 3 is a plan view of said device.

The tubular standard and the oblique cross piece are of contrasting colors.

I claim:

The ornamental design for a display device, as shown and described.

LIONEL A. CARTER.
